Serial No. 1,222,564. **NORBERT SCHREIBER AND RAPHAEL ROSENTHAL, OF LINCOLN, ILLINOIS.**

BOILER-SKIMMER.

1,222,564.

Specification of Letters Patent.

Patented Apr. 10, 1917.

Application filed June 12, 1915. Serial No. 33,658.

To all whom it may concern:

Be it known that we, NORBERT SCHREIBER and RAPHAEL ROSENTHAL, citizens of the United States, residing at Lincoln, in the county of Logan and State of Illinois, have invented a certain new and useful Improvement in Boiler-Skimmers, of which the following is a full, clear, concise, and exact description, reference being had to the accompanying drawings, forming a part of this specification.

Our invention relates to boiler skimmers, and especially to a type of boiler skimmer particularly adapted for use in locomotive boilers and in connection with the throttle valve mechanism thereof. In an application filed by us Serial No. 867,055, filed October 17, 1914, we have illustrated one form of boiler skimmer arrangement of this general character.

The principal object of the present invention is to simplify and improve the skimmer construction and its connection and arrangement in the locomotive boiler.

In the accompanying drawings Figure 1 is a plan view of a skimmer embodying our present invention;

Fig. 2 is a cross section of the skimmer and a portion of a locomotive boiler in which the same is mounted;

Fig. 3 is a view showing in longitudinal section a portion of such a locomotive boiler and the skimmer mounted therein.

In the drawings, and especially in Fig. 1 we show a skimmer comprising a pair of side members 1 and 2 extending longitudinally of one another, preferably substantially parallel to each other. The side members 1 and 2 may be made of ordinary metal pipe and are preferably closed at their ends as by caps 3—3 and 4—4. These side members or pipes 1 and 2 are provided with longitudinally extending slots or openings 5, 6, 7 and 8, the slots 5 and 6 being on opposite sides of the member 1, and the slots 7 and 8 being on opposite sides of the member 2, as shown in Fig. 2. Floats 9, 10, 11 and 12 are attached to the members 1 and 2, the floats 9 and 10 to the member 1, and the floats 11 and 12 to the member 2, said floats being preferably secured to said members by means of laterally projecting pipe sections 13—13, and 14—14, fitted to T's 15—15, and 16—16 on said members. Said floats 9, 10, 11 and 12 are preferably located between the ends

of said members 1 and 2, a highly desirable arrangement being that shown in the drawings, especially Fig. 1, wherein the floats are located respectively about a quarter of the distance from the ends of said members, whereby equal distribution of weight is secured. The floats 9, 10, 11 and 12 are preferably elongated as shown for economy of space. A cross member 20 is extended between the members 1 and 2, preferably about midway between the ends thereof. The cross member 20 may also be constructed of pipe sections, as for example vertical pipe sections 20^a and 20^b, and a horizontal top member 20^c. An outlet pipe 21 is pivotally connected with the cross member 20, as for example by a pivotal joint member or coupling 22 and the other end of this outlet pipe 21 is connected by another pivotal joint 23 with a yoke or fork member 24 forming the end of a discharge or drain pipe 25. Thus the skimming may be brought about by the device resting upon the surface of the water in a boiler, being sustained by the floats 9, 10, 11 and 12 and the refuse matter entering the members 1 and 2 through the longitudinally extending slots 5, 6, 7 and 8 thereof and passing from the members 1 and 2, to and through the cross member 20 to the outlet pipe 21, and thence to the discharge or drain pipe 25. Up and down motion of the skimming device to maintain it always upon the surface of the water, notwithstanding changes in the level of the water, is permitted by the double pivot joint arrangement at the ends of the outlet pipe 21.

The construction described is particularly advantageous for use in a locomotive boiler and is shown so mounted in Figs. 2 and 3. When thus arranged the cross member 20 is arranged over the dry pipe 26 of the locomotive and the discharge pipe 25 to which the outlet pipe 21 is connected is extended rearwardly and thence upwardly by means of a portion 25^a through the top of the locomotive boiler and thence rearwardly and downwardly by means of a portion 25^b. The latter is provided with a valve 27 which is understood to be located at some convenient place in the engine cab. This valve 27 is normally open. A T joint 28 is also provided, this joint having a restricted orifice by which a continuous blow-off or discharge may be permitted. A pipe 29 is connected with the T 28 and extending downwardly to

a convenient discharge point, the pipe 29 being provided with a valve 30 which is to be manually controlled and opened from time to time as desired. The valve 27 being 5 normally open, a continuous discharge takes place through the pipe 25^b, valve 27 and pipe 25^c to some convenient point for discharge. The pipe 29 with its valve 30 acts as a bypass arrangement to allow a pronounced discharge 10 at any time.

The discharge pipe 25 is provided with a valve 31 which is pivotally connected by rod 32 with link 33 which is in turn pivotally connected with a collar 34 on a rod 35 which 15 is understood to be the throttle lever rod connected with the usual throttle lever (not shown). Thus the actuation of the throttle lever controls the discharge of the skimmer, the discharge valve 31 being opened when 20 the throttle valve is opened, and closed when the throttle valve is closed.

It will be understood that changes and modifications within the scope of the appended claims may be made without departing 25 from the spirit of the invention.

What we claim is:

1. A boiler skimmer comprising side members provided with intake openings and a cross member connecting said side members 30 between the ends thereof, floats for supporting said side and cross members, an outlet pipe pivotally connected with said cross member, and a drain pipe to which said outlet pipe is pivotally connected.

2. A boiler skimmer comprising longitudinally extending side members provided with intake openings and an elevated cross member extending between and connected to 40 said side members, floats for supporting said side and cross members, and an outlet pipe pivotally connected with said elevated cross member.

3. A boiler skimmer comprising longitudinally extending side members provided 45 with intake openings, a cross member extending between and connected with said side members, and elevated between its ends, floats for supporting said side and cross members, an outlet pipe pivotally connected 50 with the elevated portion of said cross member, and a drain pipe to which said outlet pipe is pivotally connected.

4. The combination with a locomotive boiler of a skimmer located therein, said skimmer having longitudinally extending side members and a cross member having an elevated portion connected with said side members between the ends thereof, said cross member being extended over the dry 60 pipe of said locomotive boiler, floats for supporting said side and cross members, a discharge pipe pivotally connected to said cross member, a valve in said discharge pipe, a throttle valve and lever and a mechanical connection for actuating said discharge

valve when said throttle valve and lever are operated.

5. The combination with a locomotive boiler of a skimmer located therein, said skimmer having longitudinally extending side members and a cross member having an elevated portion connected with said side members between the ends thereof, said cross member being extended over the dry pipe of 70 said locomotive boiler, floats for supporting said side and cross members, a discharge pipe pivotally connected to said cross member, a valve in said discharge pipe, a throttle valve and lever and a mechanical connection for actuating said discharge valve when said 75 throttle valve and lever are operated, and an outlet pipe interposed between said skimmer cross member and said discharge pipe, said outlet pipe being pivotally connected at one end to said cross member of the skimmer and 80 at the other end to said discharge pipe.

6. A boiler skimmer comprising longitudinally extending side members provided with intake openings, a cross member extending between and connected with said 90 side members intermediate the ends of said members, a float provided at each end of the side members, an outlet pipe, and a tubular link connected to the cross member and the outlet pipe.

7. A boiler skimmer comprising longitudinally extending side members provided with intake openings and an elevated cross member extending between and connected to 100 said side members, floats attached to the side members and an outlet pipe connected with said elevated cross member, said cross member and said longitudinally extending side members being movable with relation to the outlet pipe.

8. A boiler skimmer comprising longitudinally extending tubular side members provided with intake openings, a cross member connected with said side members substantially midway between the ends thereof, and 110 floats connected with said side members at points between the ends thereof and the points of connection of said cross member.

9. A boiler skimmer comprising longitudinally extending tubular side members provided with intake openings, a cross member connected with said side members substantially midway between the ends thereof, 115 floats connected with said side members at points between the ends thereof and the points of connection of said cross member, and an outlet connection connected with said cross member and adapted to permit the skimmer to move upwardly and downwardly to accommodate different water levels.

10. A boiler skimmer comprising longitudinally extending side members provided with intake openings and having their ends closed, a tubular cross member connected with said side members at points substan- 120

tially midway between the ends of the latter, said cross member communicating with and forming an outlet for said side members, floats independently connected with said side members at points between the ends thereof and the connection of said cross member therewith, and a jointed outlet member pivotally connected with said cross member.

It witness whereof, we hereunto subscribe our names this 4th day of June, A. D., 1915. 10

NORBERT SCHREIBER.
